UNITED STATES PATENT OFFICE.

BRUNO VON BÜLTZINGSLÖWEN, OF NEW YORK, N. Y.

PUZZLE GAME.

Application filed February 25, 1925. Serial No. 11,472.

To all whom it may concern:

Be it known that I, BRUNO VON BÜLTZINGSLÖWEN, a citizen of the United States, residing at New York, in the county of Bronx and State of New York, have invented certain new and useful Improvements in Puzzle Games, of which the following is a specification.

This invention relates to games and has for its object to provide a puzzle game consisting of a substantially annular track having turn-tables and at least three members slidably engaging the said track, two of which are capable of being moved continuously in either direction all around the track, while the third member can be moved around the track only up to a certain obstruction either in one or the other direction. The problem to be solved with this puzzle game is to reverse the positions of two of the members located on the track on opposite sides of the obstruction, while moving them or either of them only in association with the third member.

My invention will be more fully understood by reference to the accompanying drawings in which similar reference characters denote corresponding parts and in which Fig. 1 is a plan view of my puzzle game; Fig. 2 a cross-section on line 2-2 of Fig. 1; Fig. 3 a longitudinal section on line 3-3 of Fig. 1; Fig. 4 a longitudinal section on line 4-4 of Fig. 1; Fig. 5 a top plan view of a detail thereof; Fig. 6 a central section thereof; Fig. 7 a similar section at a right angle to that of Fig. 6; Fig. 8 a top plan view of a modification of the puzzle game; Fig. 9 a cross-section on line 9-9 of Fig. 8; Fig. 10 a longitudinal section on line 10-10 of Fig. 8; Fig. 11 a longitudinal section on line 11-11 of Fig. 8; Fig. 12 a plan view of a detail of said game; Fig. 13 a side elevation thereof; Fig. 14 a section on line 14-14 of Fig. 13; Fig. 15 a top plan view of a second modification; Fig. 16 a cross-section on line 16-16 of Fig. 15; Fig. 17 a longitudinal section on line 17-17 of Fig. 15; Fig. 18 a plan view of a detail; Fig. 19 a side view thereof and Fig. 20 a section on line 20-20 of Fig. 18.

In principle, all three modifications are the same, the latter differing only constructionally.

In the drawing 10 denotes a platform substantially rectangular in shape and having rounded corners. This platform is provided

with a substantially annular track composed of a U-shaped main track 11, disc-shaped rotary track members 12 at the ends of the main track and an intermediary or branch track 13 between said rotary track members, the latter being capable of being brought to register alternately with said main and branch tracks. Slidably engaging said tracks, are members 14, 14', and 14². The members 14, 14', marked "Car 2" and "Car 1" respectively, are capable of being moved either clockwise or anticlockwise completely around said annular track. About centrally of the U-shaped track 11, there is provided an obstruction 15, the object of which is to prevent the third member 14² from being moved in any one direction completely around the track. On the platform, are initial positions 16, 17 and 18, marked "Station A", "Station B" and "Roundhouse" for the three members, and positions of destination 19, 20, 21 and 22, marked "Station 1", "Station 2", "Depot 1" and "Depot 2" for the members 14 and 14'.

Now in Figs. 1-6, the platform is in form of a hollow casing constructed of two interengaging sections 10^a, 10^b fixed to one another at 10^c. The tracks 11 and 13 in the platform and the tracks 12^a in the rotary members 12 are just plain slots, those in the rotary members or turn-tables extending diametrically and being open at one end, as at 12^b, and closed at the opposite end, as at 12^c. Each turn-table is mounted in a circular hole 10^d provided in the platform and supported on bent strips of metal 12^d eyeleted or otherwise pivoted centrally, as at 12^e, on the bottom section 10^b of the platform and fixed to the upper section by short lugs 12^f engaging peripheral notches 12^g in the edge of the disc 12 and bent over the same. The members 14, 14' and 14² are button-shaped, i. e. are formed with narrow vertical shanks 23 capable of passing through the slots or tracks and formed at their free ends with horizontal flanges 24 to prevent them from being removed from the tracks.

The obstruction 15 is in form of a loop designated in the drawing as "Tunnel" and fixed to the platform by short angular lugs 15^a projecting from the ends thereof through recesses 10^e in the upper section of the platform. The member 14² is provided with a vertical projection 14^a, which prevents the same from passing through the loop or tunnel 15. The turn-tables are each formed

with a circumferential projection 12^h to serve as a grasp, when manipulating the same, and a suitable stop (not shown) is provided, for limiting the movement thereof.

5 In the modification, according to Figs. 8-14, the platform 10' is made of a single metal plate, whose edges are bent downwardly to form a base. The turn-tables 12' are plain circular discs supported on the 10 platform and eyeleted centrally at 12^e. The tracks 11', 13' and 25 in the platform and turn-tables respectively are raised, the edges of the slots being bent both vertically upwards and horizontally. The grooves formed 15 by the vertical bends serve to slidably engage the tails 24 of the members 14, 14' and 14², while the lateral flanges formed by the horizontal bend prevent the removal of said members.

20 Instead of the loop or tunnel 15, two upwardly projecting wings or flaps 15' are provided, one at each side of the main track 11' to serve as obstructions, the same being spaced apart a distance smaller than the 25 width of the member 14², but wide enough to permit the passage of the other two members.

For limiting the movement of the turn-tables, each of them is provided with a circularly curved slot 26 into which projects a lug 10^j provided on the platform. The turn-table discs 12' are each also formed with circumferential upwardly projecting flanges 12^k, which are adapted to close the ends of 35 the tracks 11', 13', when the tracks 25 in the turn-tables are not in range with the latter.

In the modification according to Figs. 15-20, the tracks 11², 13² and 27 are made of 40 separate hollow or tubular pieces of metal substantially of rectangular cross section and slotted longitudinally. The same are riveted to the platform and turn-tables, as at 28. In every other respect, the construction is substantially the same as in the other 45 modification.

The operation is as follows:—

First. Assuming "Car 1" to occupy the position "Station B," "Car 2" the position "Station A" and the third member 14², which 50 in Fig. 15 is designated "Locomotive" to occupy the position marked "Roundhouse." It is required to move with the "Locomotive" "Car 2" from "Station A" to "Station 2" and "Car 1" from "Station B" to "Station 1" 55 and to return the "Locomotive" to the "Roundhouse," the condition being that the members 14, 14' must never be moved alone, but always in association with the member 14², the latter either in front, middle or at 60 the rear thereof.

Second. Assuming "Car 1" located at "Depot 2," "Car 2" at "Depot 1" and the "Locomotive" at the "Roundhouse." It is required to move with the "Locomotive" "Car 1" from "Depot 2" to "Station 1" and 65

"Car 2" from "Depot 1" to "Station 2" and return the "Locomotive" to the "Roundhouse," following the same rule as before.

The solutions are as follows:—

Bring member or locomotive 14² over turn-table (say the left one) onto the left side of the U-shaped track 11, (11' or 11²) and push by it the member 14 or "Car 1" from "Station A" into the tunnel 15 (or space between the obstructions 15', 15', Figs. 8 and 15). 70 Then move the locomotive back over the left turn-table, track 13 (13' or 13²) onto the right side of the U-shaped track and push by it member 14' ("Car 1") from "Station B" into said tunnel or space between the obstructions next to "Car 2." Then push both "Cars 1 and 2" with the "Locomotive" 80 in advance over the right-hand side of the U-shaped track and the right turn-table to the "Roundhouse" and "Depots 1 and 2." 85 Then with the "Locomotive," bring "Car 1" over the right turn-table into the tunnel, leaving "Car 2" at "Depot 1" and bring the "Locomotive" back over the right turn-table to "Car 2." With the "Locomotive" "Car 2" 90 is then pushed to "Station 2" over the right turn-table. After bringing the "Locomotive" over the right turn-table, straight track, left turn-table onto the left side of the main track close to "Car 1," the latter is 95 pushed by it to "Station 1" and the "Locomotive" thereupon returned to its position at the "Roundhouse."

The second problem is similarly solved.

What I claim is:—

1. A puzzle game comprising a platform having a fixed main track, a fixed branch track and at least two movable tracks of which each one is capable of being brought into range alternately with the main track 105 and branch track, at least three members capable of moving through said tracks and an obstruction at the main track preventing the passage of one of said members.

2. A puzzle game comprising a platform having a fixed main track, a fixed branch track and at least two movable tracks of which each one is capable of being brought into range alternately with the main track 115 and branch track, at least three members capable of moving through said tracks, an obstruction at the main track preventing the passage of one of said members and designations on said platform of initial positions and positions into which said members are 120 to be moved, while solving the puzzle.

3. A puzzle game comprising a platform formed with a U-shaped main track, two turn-tables each formed with a track closed at one end and open at the other end and each arranged near one end of said main track, an intermediate track extending between said turn-tables, the track on each of said turn-tables being capable of being 125 brought into range alternately with said 130

main track and intermediate track, a number of members capable of moving along said tracks, means at the main track for preventing the continuous movement of one of said members through the main track and designations on said platform for the initial positions of and the positions of destination for said members.

4. A puzzle game comprising a platform formed with a U-shaped main track or groove, two turn-tables each formed with a track closed at one end and open at the other end and each arranged near one end of said main track, an intermediate track

extending between said turn-tables, the track 15 on each of said turn-tables being capable of being brought into range alternately with said main track and intermediate track, a number of members capable of moving in said tracks, means at the main track for preventing the continuous passage of one of said members through the main track, means for limiting the movement of said turn-tables and designations on said platform for the initial positions of and the positions of 25 destination for said members.

In testimony whereof I affix my signature.

BRUNO VON BÜLTZINGSLÖWEN.
